UNITED STATES PATENT OFFICE.

EDWARD G. THOMAS, OF NEW YORK, N. Y., ASSIGNOR TO LAMSON CONSOLIDATED STORE SERVICE COMPANY, OF NEWARK, NEW JERSEY, A CORPORATION OF NEW JERSEY.

CARRIER FOR PNEUMATIC-DESPATCH TUBES.

No. 861,334.

Specification of Letters Patent.

Patented July 30, 1907.

Application filed August 9, 1905. Serial No. 273,466.

To all whom it may concern:

Be it known that I, EDWARD G. THOMAS, of New York, in the borough of Manhattan and State of New York, have invented certain new and useful Improvements in Carriers for Pneumatic-Despatch Tubes, of which the following is a specification.

My invention relates to improvements in carriers adapted for use in pneumatic despatch tube apparatus and its principal object is to provide a simple and efficient means for constructing the carrier shell, and for attaching to it the felt head or buffer, and a yielding ring at the opposite end of said carrier shell.

In the accompanying drawings which illustrate a construction embodying my invention:—Figure 1 is an exterior view of the carrier showing the open end of same in section. Fig. 2 is a sectional view on line $x-x$, Fig. 1 looking in direction indicated by arrow. Fig. 3 is a sectional view of a portion of Fig. 1 showing method of fastening buffer to shell or cylinder. Fig. 4 is a section on line $y-y$ Fig. 3.

Like letters of reference refer to like parts throughout the several views.

The shell consists of a tube of cylindrical or other form, which carries an internal flange at one end. A plate H is located inside the shell, and may be centered by inwardly projecting ribs L formed in the carrier shell.

The buffer or head B of the carrier, is composed of some yielding material such as felt, and is secured to the plate or washer H by the screws J. The screws J may pass through holes in the plate H, and be provided with nuts upon the back but the preferable construction is to tap holes in the plate H and thus do away with the necessity of nuts, which are inconvenient to put in place because of their location inside the shell. The heads of the screws J may be prevented from tear-

ing the felt by the washer I, and a piece of felt K may be inserted in the hole of the head B to cover the heads of the screws J.

The rear or open end of the carrier A is provided with an external flange E against which rests the felt ring F, which, when placed in the position shown in Fig. 1 is held against displacement by the split metal ring D sprung into the circumferential recess C and pressing against the said felt ring F. When the ring F becomes worn from use, the felt ring is removed, and another one substituted, after which the split ring D is sprung back into place.

Having thus described the nature of my invention and set forth a construction embodying the same, what I claim as new and desire to secure by Letters Patent of the United States is:

1. In a carrier for pneumatic despatch tube apparatus, a shell carrying an external flange at one end, a yielding ring adapted to fit over said shell and against said flange, a circumferential recess or groove in said shell, and means co-operating with said recess or groove for engaging and holding said yielding ring in position.

2. In a carrier for pneumatic despatch tube apparatus, a shell carrying an external flange at one end, a yielding ring adapted to fit over said shell and against said flange, a circumferential recess or groove in said shell, and a split ring adapted to be sprung into said recess or groove and to engage said yielding ring and hold the same in position.

3. In a carrier for pneumatic despatch tube apparatus, a shell carrying an external flange at one end, a yielding ring adapted to fit over said shell and against said flange, and a removable ring for retaining said yielding ring in position thereon.

In testimony whereof, I have signed my name to this specification in the presence of two subscribing witnesses, this thirty first day of July A. D. 1905.

EDWARD G. THOMAS.
